UNITED STATES PATENT OFFICE.

JOHN V. STEWART AND FRANK G. WERTZ, OF JOHNSTOWN, PENNSYLVANIA.

SWITCH STAND.

1,404,491.

Specification of Letters Patent. Patented Jan. 24, 1922.

Application filed October 5, 1921. Serial No. 505,577.

To all whom it may concern:

Be it known that we, JOHN V. STEWART and FRANK G. WERTZ, citizens of the United States, and residents of Johnstown, in the county of Cambria and State of Pennsylvania, have invented certain new and useful Improvements in Switch Stands, of which the following is a specification.

This invention relates to switch stands, and has for its principal object the provision of a switch stand having a novel lever mechanism for operating the target and switch rod.

Another object is to provide a switch stand having means for locking the internal mechanism against movement when the switch is accidentally tripped.

A further object is to provide a switch stand that will be easy to operate, strong, and durable.

The above and other objects and advantages will be brought out in the following specification and illustrated in the accompanying drawings, in which—

Figure 1 is a top plan of a switch stand constructed in accordance with our invention.

Figure 2 is a side elevation of the same.

Figure 3 is a top plan of the stand with the top of the casing removed to show the internal mechanism of the stand.

Figure 4 is a sectional elevation of the stand developed substantially on the irregular line IV—IV of Figure 3.

Figure 5 is an elevation of the assembled upper and lower spindles forming the target shaft and the spindle arm.

Figure 6 is a detail perspective view of the lower spindle.

Figure 7 is a detail perspective view of the upper spindle.

Figure 8 is a detail perspective view of the spindle arm.

Figures 9 and 10 are detail perspective views of the adjustable wedges for the lower spindle.

Figure 11 is a plan of the hand operating lever and crank arm.

Figure 12 is a fragmentary detail elevation of the connecting jaw of the operating crank arm.

Referring more particularly to the drawings, the letter A designates the casing of the stand as a whole, which is composed of upper and lower sections 2 and 3 which are open at one side forming a doorway which

is closed by a door 4. The lower section of the casing is provided at diametrically opposite sides with the usual feet 5 for securing the stand to a suitable base. 60

The upper and lower sections 2 and 3 are provided with vertically aligned bearing apertures in which the ends of a vertical shaft composed of upper and lower spindles 6 and 7, respectively, are journaled. The 65 spindle 7 is provided with a recess or socket 8 in which the lower end 9 of the spindle 6 is journaled. The spindles cooperate to form what is ordinarily termed the target shaft of the stand, and the upper end of the 70 upper spindle projects beyond the casing and carries a target 10, while the lower end of the spindle 7 projects through the casing and has a crank arm 11 secured thereon by a breakable collar 12 which is pinned on the 75 lower end of the spindle 7. The breakable collar 12 is provided with a pair of lugs 13 either of which is adapted to fit between a pair of ears 14 on the crank arm 11. Therefore, if the switch is accidentally tripped 80 the shock will break the lug 13 engaged between the ears 14 on the crank and release said crank so that it may turn freely on the spindle 7, thus preventing the damaging of any of the internal mechanism of the stand. 85 If one of the lugs 13 is broken, the collar may be reversed and the other lug engaged between the ears 14.

A switch rod link 15 is pivotally secured to the crank arm 11 and adapted to be connected to a switch rod, (not shown).

The lower spindle 7 is provided with a slotted arm 16 having serrations 17 on its side faces. A pair of adjustable wedge members 18 and 19 are mounted on the opposite sides of the arm 16 and comprise a curved or rounded wedging head 20 and an apertured body portion 21. The inner faces of head 20 and body portion 21 are on the same plane and are provided with serrations 100 22 adapted to mesh with the serrations 17 on the side faces of the arm 16.

The upper end or head 20 of the members 18 and 19 projects at right angles over the arm 16 to form a support, and the members 105 are secured or locked in position on the arm by a bolt 23 which passes through the apertures in the body portion 21 of the wedges and through the slotted body of the arm 16.

The upper spindle 6 has an enlarged body portion 25 provided with an arched aperture 26, bearing orifices 27, and projecting jaws

or wings 28. The wings 28 are spaced apart and have their inner surfaces inclined or flared outwardly so as to form a bearing surface for the wedges 18 and 19. That is, the wings 28 engage the wedges 18 and 19 and as the upper spindle is rotated, the inner surfaces of the wings ride on and bear against the wedges so as to force the lower spindle to rotate, thus moving the crank arm 11 and operating the switch.

It will be noted that the wedges 18 and 19 are adjustably secured to the arm 16 and may be adjusted longitudinally thereof. Therefore, if the wedges 18 and 19 be moved outwardly or toward the free end of the arm 16, the upper spindle will be permitted a certain amount of free movement before the jaws contact with the wedges.

The upper spindle 6 is adapted to be rotated by a toggle like connection, which comprises a spindle arm or lever 29, a crank arm 30, and operating lever 31.

The spindle arm 29 has an apertured head portion 32 journaled on a pin 33 mounted in the bearing orifices 27 of the upper spindle, a shank portion 34, and a bearing portion 35.

The bearing portion 35 of the spindle arm is adapted to be engaged in an open sided head or yoke 36 on the end of the crank arm 30, which arm is journaled in a bearing 37 formed in the casing of the stand. The other end of the crank arm 30 is secured by welding or otherwise, to one end of the operating lever 31 which is provided at its free end with a counterweight 39.

As the lever 31 is lifted and swung to the opposite side of the casing, it will rotate the crank arm 30 in the bearing 37, thus raising and rocking the crank end of the arm and spindle 29 in the direction the lever 31 is swung. That is, as the crank arm 30 is rotated, the crank end will move upwardly and sidewardly so as to rock the spindle arm 29 about the pin 33 and rotate the upper spindle 6. The rotating movement of the upper spindle 6 will be communicated through the jaws or wings 28 and wedges 18 and 19 to the lower spindle, thus rotating the lower spindle 7 and operating the crank arm 11 and switch rod link 15 which is connected to the switch rod.

As has been stated, the wedges 18 and 19 are adjustably mounted on the arm 16 and may be moved toward or away from the wings 28 of the upper spindle to vary the free movement of the operating mechanism of the stand. That is, if the wedges 18 and 19 are moved a predetermined distance away from the jaws or wings 28 the upper spindle 6, spindle arm 29, crank arm 30, and lever 31 may be moved a predetermined distance before the wings engage the wedges 18 and 19 to move the switch. The preferred position of the wedges 18 and 19 will be

that which will permit the lever 31 to be moved upwardly to its vertical position before the wings 28 engage the wedges.

The spindle arm 29 is provided with lugs 40 projecting from each side of the shank 70 portion 34 and ends of an upwardly projecting lug 41 on the lower section of the casing, thus preventing the movement of the spindles when the switch is accidentally trialed or otherwise forced. The weakest connection in the whole train of mechanism is the lug 13 on the collar 12. Therefore, if the switch is trialed this lug will break and the remainder of the mechanism will be uninjured.

While we have shown and described one specific embodiment of our invention, we do not wish to be limited thereto since various modifications may be made without departing from the spirit of our invention as defined in the appended claims.

We claim—

1. A switch stand comprising a casing, upper and lower spindles journaled in said casing, a crank arm carried by said lower spindle and adapted to be connected to a switch rod link, a target carried by said upper spindle, lever means for rotating said upper spindle, and means actuated by said upper spindle for rotating said lower spindle.

2. A switch stand comprising a casing, a spindle journaled in said casing, a target carried by said spindle, a spindle arm pivoted for vertical movement on said spindle, a crank arm journaled in said casing and operatively engaged on said spindle arm, and means for rocking said crank arm to thereby actuate said spindle arm so as to rotate said spindle.

3. A switch stand comprising a casing, upper and lower spindles journaled in said casing, a crank arm carried by said lower spindle and adapted to be connected to a switch rod link, a target carried by said upper spindle, a spindle arm pivotally mounted for vertical movement on said upper spindle, a crank arm journaled in said casing and operatively engaged on said spindle arm, a lever for rocking said crank arm to thereby actuate said spindle arm so as to rotate said upper spindle, and means actuated by said upper spindle for rotating said lower spindle.

4. A switch stand comprising a casing, upper and lower spindles journaled in said casing, a crank arm carried by said lower spindle and adapted to be connected to a switch rod link, a target carried by said upper spindle, a spindle arm pivotally mounted for vertical movement on said upper spindle, a crank arm journaled in said casing and operatively engaged on said spindle arm, a counterweighted hand lever secured to and adapted to rock said crank

arm to thereby actuate said spindle arm so as to rotate said upper spindle, and means actuated by said upper spindle for rotating said lower spindle.

5. A switch stand comprising a casing, upper and lower spindles journaled in said casing, a crank arm carried by said lower spindle and adapted to be connected to a switch rod, a target carried by said upper spindle, a spindle arm pivotally mounted for vertical movement on said upper spindle, a crank arm journaled in said casing and operatively engaged on said spindle arm, a lever adapted to rock said crank arm to thereby actuate said spindle arm so as to rotate said spindle, means operatively connecting said upper and lower spindles, said means including a pair of wing members projecting from said upper spindle, and engaging a pair of wedge members projecting from said lower spindle.

6. A switch stand comprising a casing, upper and lower spindles journaled in said casing, a spindle arm pivotally mounted for vertical movement on said upper spindle, a crank arm journaled in said casing and operatively engaged on said spindle arm, a lever adapted to rock said crank arm to thereby actuate said spindle arm so as to rotate said spindle, means operatively connecting said upper and lower spindles, said means including a pair of wing members projecting from said upper spindle, and engaging a pair of wedge members projecting from said lower spindle.

7. A switch stand comprising a casing, upper and lower spindles journaled in said casing, a crank arm carried by said lower spindle and adapted to be connected to a switch rod, a target carried by said upper spindle, a spindle arm pivotally mounted for vertical movement on said upper spindle, a crank arm journaled in said casing and operatively engaged on said spindle arm, a lever adapted to rock said crank arm to thereby actuate said spindle arm so as to rotate said spindle, means operatively connecting said upper and lower spindles, said

means including a pair of wing members projecting from said upper spindle, a slotted arm projecting from said lower spindle, and a pair of adjustable wedge members carried by said slotted arm and projecting into the path of said wing members.

8. A switch stand comprising a casing, a vertically disposed shaft journaled in said casing, a lever pivotally connected to said shaft for vertical pivotal movement relative thereto, a crank arm operatively connected to said lever and journaled in said casing, and a hand lever secured to said crank arm adapted to be swung from side to side to rotate said crank arm, said crank arm in turn lifting and swinging said first named lever to rotate said shaft.

9. A switch stand comprising a casing, a vertically disposed shaft journaled in said casing, a crank arm secured on the lower end of said shaft and adapted to be connected to a switch rod link, a target secured to the upper end of said shaft, a lever pivotally connected to said shaft for vertical pivotal movement relative thereto, a crank arm operatively connected to said lever and journaled in said casing, and a hand lever secured to said crank arm adapted to be swung from side to side to rotate said crank arm, said crank arm in turn lifting and swinging said first named lever to rotate said shaft.

10. In a switch stand having a casing, and a vertically disposed shaft journaled in said casing, said shaft being composed of upper and lower spindle members, means for rotating said upper spindle, and means connecting said upper and lower spindles to cause said lower spindle to rotate with said upper spindle after said upper spindle has revolved a predetermined distance relative to said lower spindle, said last named means being adjustable to vary the amount of rotation of said upper spindle relative to said lower spindle.

In testimony whereof we have hereunto set our hands.

JOHN V. STEWART.
FRANK G. WERTZ.
